UNITED STATES PATENT OFFICE.

DAVID H. MORRISON, OF DAYTON, OHIO.

LIFTING-JACK.

SPECIFICATION forming part of Letters Patent No. 228,830, dated June 15, 1880.

Application filed April 26, 1880. (No model.)

To all whom it may concern:

Be it known that I, DAVID H. MORRISON, of Dayton, in the county of Montgomery and State of Ohio, have invented certain new and useful Improvements in Lifting-Jacks; and I do hereby declare the following to be a full, clear, and exact description of the same.

My invention relates to an improvement in that class of lifting-jacks which employ rack lifting-bars instead of screws, and my object is to produce a jack which in its operating parts shall be as free as possible from friction, and shall be capable of raising extremely heavy objects without liability of its parts breaking or giving away.

The novelty of my invention consists in employing in a jack the combined forces of a toggle and cam or eccentric pressure for a lifting power, with the parts so arranged that firm solid bearings are obtained for the rack-operating devices, which re-enforce each other and do not depend upon pivot pins or bolts, and whereby the friction occasioned by the operation of these parts is reduced to a minimum.

The novelty further consists in the construction and combination of the parts, all as will be herewith set forth and specifically claimed.

In the accompanying drawings, Figure 1 is a perspective view of my improved jack. Fig. 2 is a central sectional view, in side elevation, of the same. Fig. 3 is a rear elevation of the middle portion of the jack.

The shell or casing A may be of any desired construction. In this instance it is supported by a base, B, with lateral ribs or webs C, to distribute the strain; and it contains three compartments—one for the lifting rack-bar, a second for the holding-dog, and the third for the lifting mechanism. The rack-bar D carries upon its top, which projects from an opening in the case, the usual or any serrated head-piece, and its lower end is formed into a foot, a, somewhat narrower than the rack-bar, which foot projects through a vertical slot of corresponding size in the front plate of the case, as represented.

The division-wall E, in connection with the side and front walls of the case, form a snug sheath for the rack-bar, and allow it only a vertical play. The foot a is used in starting

to raise objects sufficiently to get the head of the lifting-bar under them, or to raise objects for a short distance only, and being narrower than the rack-bar, of which it forms a part, said bar has a bearing upon the front plate of the case on each side of the slot.

In the bottom of the lifting-mechanism compartment of the case is an integral pillow-block or step, b, in the recess of which is supported a vibrating arm or bar, F, of the shape shown, having its upper end concave to form a socket for the cam bearing-surfaces c of the actuating-lever G. This lever, of the shape represented, is provided with a socket for the handle H, and is supported in the case by the vibrating arm F, upon which the integral cam c rests and with which it articulates, and by a bolt, e, which, passing through the lever concentrically with the cam d, has upon its ends square heads or nuts f, which are confined in vertically oblong rectangular apertures or mortises g in the sides of the case, as shown particularly in Fig. 1; also, hung upon the bolt or pin e, straddling the cam d, and bearing thereon, is the slotted lifting-dog I, Figs. 2 and 3, which is inclined toward the rack-bar, with which it engages at its upper end by means of the teeth i, as represented. The head or upper end of the dog is provided with a lateral stud or knob, j, which projects through an aperture, k, in the side of the case, as seen in Fig. 1. If desired, there may be two knobs, one projecting on each side through corresponding apertures in the sides of the case. These apertures should be of sufficient size to permit the necessary vertical movement of the dog in raising the rack-bar and the necessary swinging motion in disengaging itself from the rack-bar and descending to its former re-engaging position.

It is to be observed that while the bearing portions c d of the lever are segments of true circles, yet they are located eccentrically to each other, and practically form cam bearing-surfaces, of which the lower one, c, traveling in the socket of the vibrating arm F, as the lever is brought down, causes the upper one, d, to rise as it turns, thus forcing the dog I upward and raising the rack-bar.

It is to be further noticed that while the le-

ver is descending and the segment *d* is rising as it turns on its center, the cam *c* is also, while turning, swinging in the arc of a circle upon the shifting center of the segment *d*. 5 This motion of the cam *c* causes the arm *F* to move inward with the effect of a toggle, and thus increases the lifting effect of the cam. It is also to be observed that while the dog *I* is being raised it does not change its inclination, but moves directly up, so that its force is exerted always in the same line, running through its points of greatest resistance. 10 This motion of the dog while ascending is due to the heads of the bolt *e* being confined in the vertical apertures *g*, and, further, to the upper end of the dog engaging with the rack-bar, which is limited to a vertical motion by its sheath. 15 It is to be particularly noticed that while the pin *e* serves to connect the parts, it is in no sense a fulcrum, but that all the strain and force is borne by the solid members, which, articulating as they do, resolve it upon the base of the jack, which is firmly supported. 20 25 The dog *I* is further so set or inclined that when the operating-lever is raised it falls into engagement with the rack-bar by its gravity when the jack is upright; but to insure its positive engagement in any position in which 30 the jack may be placed, I have formed sufficient swell in that portion of the web of the lever which enters the slot *l* of the dog to cause the contact of said swell *m* with the end wall of the slot, when the lever is raised and 35 the teeth of the pawl are just on the point of engaging with the rack-bar, so as to force the dog into engagement with the rack-bar if its own weight and then position is not sufficient. 40 45 To hold the rack-bar up at each successive hoist I employ a gravitating dog, *L*, which is seated in a recess in the upper compartment of the case, as seen in Fig. 2. This seat for the dog is formed by the division-wall *n*, integral with the case, and the dog *L* is sufficiently inclined to insure its engagement by its gravity. It has a series of engaging teeth, *o*, as represented, and is free to vibrate upon its solid seat without the employment of pivot-pins. 50 55 Like the dog *I*, it has a stud or knob, *p*, projecting from its upper end, which extends through an aperture, *r*, in the side of the case. When it is desired to lower the rack-bar it is only necessary to disengage the dogs *I* and *L* successively or simultaneously by means of the knobs *j* and *p*. The shape of the teeth of the rack-bar is immaterial, provided the dogs will be automatically released. The form herein shown 60 is, however, considered best for strength.

The principles of construction and operation involved in my jack produce an implement which is simple, durable, and extremely powerful, with a minimum of friction.

Having thus fully described my invention, I 65 claim—

1. In a lifting-jack, the combination, with the rack-bar, of a lifting-dog, a vibrating support-arm, and an interposed cam or its equivalent, whereby, upon turning said cam or its equivalent, a combined toggle and cam pressure is exerted upon the rack-bar. 70

2. In a lifting-jack, the combination, with the rack-bar, of a lifting-dog having a fixed unvarying upward motion, a vibrating support-arm, and an interposed actuating-cam, substantially as described. 75

3. In a lifting-jack, the combination, with the rack-bar, of a lifting-dog, a vibrating support-arm set in a solid socket, and an interposed actuating-cam, substantially as described. 80

4. In a lifting-jack, the actuating-lever having at its lower end a cam bearing-surface articulating with a vibrating arm, and having 85 also a second bearing-surface turning on a shifting center, in combination with a lifting-dog and its engaging rack-bar, substantially as described.

5. In a lifting-jack, the combination, with 90 a lifting-dog, an actuating-cam, and a vibrating toggle-arm, of a bolt or pin connecting said dog and actuating-cam, and having upon its ends square or rectangular heads recessed in vertically-oblong slots, substantially as and 95 for the purpose specified.

6. In a lifting-jack, the combination of the lifting-dog, a vibrating arm set in a solid socket, and an interposed actuating-cam, the parts being so connected and articulated that 100 the lifting-strain is thrown directly upon the solid support of the vibrating arm, substantially as described.

7. In a lifting-jack, the combination, with 105 lifting-dog, of its actuating-lever, the parts being so arranged that the lever serves to throw the dog into engagement with its rack-bar at each upward stroke, substantially as described.

8. In a lifting-jack, the swinging gravitating dog *L*, set in a solid socket integral with the shell of the jack, and provided with a releasing pin or knob extending to the outside, substantially as described. 110

In testimony whereof I have hereunto set 115 my hand.

DAVID H. MORRISON.
